UNITED STATES PATENT OFFICE

LOUIS TORCH, OF CHICAGO, ILLINOIS, ASSIGNOR TO DELLA RABIN, OF CHICAGO,
ILLINOIS

ELEVATOR DOOR CONTROL

Application filed February 17, 1930. Serial No. 428,929.

This invention relates to elevator doors and more particularly to operator controls therefor, although certain features thereof may be employed with equal advantage for other purposes.

It contemplates more especially the provision of novel means for controlling the elevation and descent of elevator doors at floor landings without resort to intricate electrical circuits and operators.

Elevator door operators of known design have not proven entirely satisfactory in that they are intricate in construction, expensive and not entirely dependable in operation. Moreover, their control of door movement is not such as to prevent slamming and for that reason soon impair the doors as well as the operation thereof.

Slamming is especially prevalent in heavy duty industrial elevator doors and more particularly with double or meeker type doors. The power operators therefor ordinarily function independently of the elevator power source of locomotion, and for that reason create a comparatively large operating cost aside from the maintenance thereof in effecting the elevation and descent of the doors for closing and opening the elevator shaft for egress and ingress as the occasion may require. This is entirely obviated with the instant invention in that the elevator furnishes the motivating power for opening and closing the doors within full control to prevent slamming or other destructive impacts.

One object of the present invention is to simplify the construction and improve the operation of devices of the character mentioned.

Another object is the provision of novel means for controlling the opening and closing of elevator doors responsive to the approach or receding movement, respectively, of the elevator with respect to floor landings.

Still another object is the provision of means in conjunction with an elevator car for automatically elevating and releasing the doors responsive to a predetermined movement and position thereof.

A further object is to provide novel cooperating means for attachment to an elevator

car and shaft doors to effect the opening and closing thereof responsive to predetermined movement of the elevator car, thereby controlling the ascent and descent thereof.

A still further object is the provision of means for normally locking an elevator door in its closed position for release prior to door displacement responsive to the movement of the elevator car.

Still a further object is the provision of a novel latch and camming bracket in the path thereof for cooperation with a trip to effect the displacement of the latch for a predetermined distance entirely controlled by the camming bracket which effects the release thereof.

An additional object is the provision of novel means in conjunction with an elevator car to effect opening of shaft doors and control the closing thereof without slamming or other destructive impacts.

Other objects and advantages will appear from the following description of an illustrated embodiment of the present invention.

In the drawings:

Figure 1 is a sectional view in elevation of an elevator car viewed from the elevator shaft.

Figure 2 is a fragmentary view taken substantially along line II-II of Figure 1.

Figure 3 is a fragmentary sectional view in elevation taken substantially along line III-III of Figure 1.

Figure 4 is a fragmentary view in elevation taken from the interior of the shaft of the doors in their open position.

Figure 5 is a similar view of a gate mounted in conjunction with an elevator doorway for operation and control in accordance with the teachings of the instant invention.

Figure 6 is a sectional view taken substantially along line VI-VI of Figure 4.

Figure 7 is a sectional view taken substantially along line VII-VII of Figure 4.

Figure 8 is a plan view of the trip which is mounted for attachment to the elevator car for traverse therewith in a manner shown in the preceding figures.

Figure 9 is a sectional view taken substantially along line IX-IX of Figure 8.

Figure 10 is a sectional view taken substantially along line X—X of Figure 1 when the doors are in their open or dotted line position and Figure 4 when viewed in connection with the opposite side bracket.

Figure 11 is a sectional view taken substantially along line XI—XI of Figure 1 when the doors are in their open or dotted line position and Figure 4 when viewed in connection with the opposite side bracket.

Figure 12 is a front view in elevation of the latch and camming bracket disclosed in Figure 10, parts thereof being broken away to clarify the showing.

Figure 13 is a front view in elevation of the latch and camming bracket disclosed in Figure 11, parts thereof being broken away to clarify the showing.

Figure 14 is a front view in elevation of the latch and camming bracket shown in co-operation with the trip which engages the latch for vertical movement upwardly to initially contact with the camming bracket.

Figure 15 is a similar view of the latch, camming bracket and trip in a further elevated position coincident with the pivotal displacement of the trip by the camming surface for an extent almost sufficient to loose or release the latch.

Figure 16 is a similar view of the latch, camming bracket and trip with the latter elevated to an extent for camming along the bracket beyond the latch to a position permitting release of the latter so that the doors may close.

The structure selected for illustration is shown in association with a building wall 10 having a substantially rectangular opening 11 provided therein to define a doorway or opening 12 to an elevator shaft 13 where passage over the floor 14 is necessary for ingress or egress from an elevator 15 which is slidably mounted for vertical movement within the shaft 13. In order to effect the closure of the doorway 12 to preclude any passage therethrough as well as decrease the fire hazard to a minimum, a door 16 is mounted in confronting bracket guides 17 and 18 fixed to the wall of the shaft 13 on both sides of the opening 12 for guiding the movement thereof along a predetermined vertical path. The closure or door 16 comprises, in this instance, a top section 19 and bottom section 20 which have beaded or otherwise reinforced meeting edges 21 for opposed movement in accordance with meeker type structures of known design.

The door sections 19 and 20 are inter-connected by means of tension transmitting wires or ropes 22 which travel over peripherally grooved sheaves 23 revolvably mounted in furcated brackets 24 clamped or otherwise secured to the guides 17 and 18 by means of lugs 25 fixed thereto above each opening 65 in the elevator shaft 13. One end of each of

the wires 22 is anchored to latches 26 secured to the top door section 19 proximate to the meeting edge 21 thereof just inside of the door guides 17 and 18. Accordingly, the other extremity of each of the wires 22 is anchored to a bracket 27 as at 28, the bracket 27 being attached to the lower door section 20 as at 29 proximate to its meeting edge 21 in alignment with the latch 26. As shown, the brackets 27 are provided with a raised intermediate portion 30 to accommodate the guides 17 and 18 for termination in latches 31 which confront the elevator shaft 13 in proximate spaced relation therewith. The door sections 19 and 20 are balanced so that with the release of the latches 26 and 31, they will gravitate to closed position with the sections in meeting contact to close the doorway 12.

An elevator car 15 is mounted for vertical movement in the shaft 13 which is provided with suitable guides or tracks therefor in accordance with commercial practice, thereby guiding the ascent and descent thereof in a predetermined vertical lane of travel. As shown, the elevator 15 is of such size and configuration so that the interior thereof will communicate with the doorway 12 when the floor 14 of the structure is in alignment with the floor 32 of the elevator car 15. Of course, the ceiling 33 of the elevator car 15 is spaced from the floor 32 thereof so that it will extend beyond the opening or doorway 11 to permit creeping of the car 15 downwardly responsive to sustaining a load therein or in the opposite direction subsequent to load removal.

In order that the door sections 19 and 20 may be opened or closed for control by the movement and position of the elevator car 15, the latter is provided with trips 34 and 35, totaling in this instance four, which are securely fastened thereto in any appropriate position to cooperate with the latches 26 and 31. In this instance, the trips 34 are fixed to the side walls of the elevator car 15 for confronting extension therein proximate to the ceiling 33 thereof to cooperate with the latches 26 fixed to the top door section 19 while the trips 35 are secured to the exterior side walls of the elevator car 15 for extension within the elevator shaft 13 below the floor 32 to cooperate with the latches 31 fixed to the lower door section 20. To this end, the trips comprise an angular plate 36 having one side 37 thereof apertured to constitute the securing bracket while the other angular wall 38 serves to sustain a central screw 39 which serves as a pivot for a pin 40 having aligned cylindrical extremities 41 and 42.

In order to maintain the pin 40 in a predetermined position, coil springs 43, in this instance two, are interposed between aligned lugs 44 and 45 fixed to the pin 40 and clip 46, respectively, the latter being secured to the

angular face 38 of the bracket 36 by means of fasteners 47. In consequence thereof, the pin 40 will be urged in a clockwise direction (viewed from Figure 8) about the pivot 39 for normal disposition in parallelism with the angular edge of the bracket 36 owing to projections 48 fixed to the plate 38 on opposite sides of the pivot 39 in the path of the pin 40, thereby limiting the clockwise displacement of the pin 40 responsive to the urge of the springs 43. The trips 34 and 35 are mounted so that the pins 40 normally extend in parallelism with the side walls of the elevator car 15 so that the extremities 41 thereof will project beyond the forward edge 49 thereof in the path of the latches 26 and 31.

The latches 26 and 31 are shaped to provide wedge extensions 50 and 51, respectively, which are inclined in opposite directions to present trip engaging flat edges 52 and 53, respectively. As shown, the wedge extensions 50 and 51 are bent from the latch brackets 26 and 31, respectively, for spaced parallelism therewith for movement with the door sections 19 and 20 in the path of and beneath cams 54 which terminate in parallel spaced attaching brackets 55 apertured to receive fasteners 56 therethrough for attachment to the elevator shaft 13 in the path of the latches 26 and 31. The cams 54 are provided with converging edges 57 which are positioned in the path of the trip pin extensions 41 so that the latter may effect the engagement thereof together with the latches 26 and 31 which slidably move therebetween in a manner disclosed in Figures 10 and 11.

It is to be noted that the cams 54 are positioned for secured to the guides 17 and 18 proximate and within the region of the extreme open positions of the top and bottom sections 19 and 20 comprising the door 16, it being worthy of note that the latches 26 and 31 become concealed therein responsive to the engagement of the trip pin extensions 41 with their edges 52 and 53, respectively, during the normal alignment of the pins 40 just prior to engaging the camming edges 57 in a manner disclosed more fully in Figures 14 to 16 inclusive, since the pin 41 carried by the elevator car 15 will abut against the engaging latch edges 52 and 53 to effect the separation of the door sections 19 and 20 responsive to the approach of the elevator car from either direction to the doorway 12 for aligned communication therewith at which position the door 16 is completely opened to permit ingress and egress through the doorway 12.

In this connection it is of utmost importance to appreciate that the trip pin 41 engages the latch edges 52 responsive to the ascent of the elevator car in its approach to the doorway 12, thereby elevating the door section 19 and effecting the corresponding descent of the door section 20 owing to the tie rope connection 22 therebetween. The

ascent of the elevator together with the opening or separation of the door sections 19 and 20 continues until such a time as the trip pins 41 engage the camming edge 57 of the brackets 54 (see Figure 15) at which time the pins 41 of the trips 34 are pivoted to approach each other for an extent sufficient to release or become disengaged from the latches 26. When this occurs, the door sections 19 and 20 gravitate toward each other for closing the doorway 12; however, the closing speed of the door sections 19 and 20 is within the receding movement of the elevator car 15 in that the continued upward movement thereof will cause the pins 41 of the trips 35 to become engaged by the latch edges 53 of the lower door section 20.

In consequence thereof, the door sections 19 and 20 cannot approach each other at a speed in excess of the initial acceleration of the elevator as it recedes from the doorway 12. This is effected regardless of the directional receding movement of the elevator car 15 in that one or the other of the latch edges 52 or 53 of the door sections 19 and 20, respectively, will engage the pins 41 to control the closing movement thereof to an extent preventing slamming or other destructive impacts which occur with meeker or other doors of known construction and design.

With the arrangement of parts thus far described it will be apparent that the movement of the elevator car 15 within the shaft 13 in either direction will open the door 16 responsive to the elevator's approach to the doorway 12, for the trips 34 situated proximate to the top of the elevator car, in this instance interiorly thereof, will engage the latches 26 while the trips 35, in this instance two, fixed exteriorly of the elevator car 15 to the side walls thereof below the floor 32 will engage the latches 31, thereby effecting the operation and control of the door sections 19 and 20 regardless of the directional movement thereof. Similarly, the closing or approach of the door sections 19 and 20 will be controlled by the pins 41 on either of the trips 34 or 35 depending upon the receding direction of the elevator car 15 with respect to the doorway 12.

During the receding ascent of the elevator car 15 the lower trips 35 are effective in controlling the closing speed of the door sections 19 and 20 owing to the engagement of the latch edge 53 with the pins 41 thereof. Similarly with the receding descent of the elevator car 15 from the doorway 12, the pins 41 mounted on the trip 34 control the speed with which the sections 19 and 20 close owing to the engagement of the meeting edge 21 thereof with the pins 41. It is obvious that the latches 26 and 31 as well as the cams 54 may be varied in position with respect to each other within a wide range depending upon elevator car and shaft construction, size

and configuration. The timing of the trip action of the pins 41 as well as the release of the latches 26 and 31 is capable of adjustment and variation to meet the requirements of any particular installation, and consequently the positions of the trips 34 and 35 will correspondingly vary or be changed to time the opening of the door sections 19 and 20 as well as to effect the release thereof at a predetermined receding position of the elevator car 15 from the doorway 12 in either direction.

It is apparent, therefore, that a novel means has been provided to operate a closure 16 for an elevator shaft doorway 12 without resort to any intricate electrical circuits, apparatus or power consuming operators. Moreover, mechanical means of this character not only serve to open the doors with precision, but also retard the closing thereof to an extent sufficient to preclude destructive slamming and impact which impairs the operation of doors of known construction within a very short time. Now then, the elevator car 15 moves for alignment with any selective landing 14 of a building structure, and at that time the trip pins 41 are still in engagement with the latches 26 or 31 depending upon the directional approach of the elevator car so that the meeting edges 21 and 21' of the door sections 19 and 20 will be separated for an extent sufficient to assume a position above and below the horizontal edges of the rectangular opening or doorway 12 (see dotted line position thereof—Figure 3), thereby permitting the elevator car 15 to creep under load, a common occurrence with known elevator structures.

It is apparent from the above description that the trip pins 41 are normally urged by the springs 43 for alignment with the latches 26 and 31. For that reason, the ascent or descent of the elevator car 15 past a doorway 12 would open and close the closure 16 or the sections 19 and 20 thereof even though it was not the desire or necessity of the elevator operator to stop at each landing. To avoid this unnecessary operation of the doors 16, means are provided to normally displace the trip pins 41 out of the path of the latches 26 and 31 so as to be effectless in operating the doors 16 unless the elevator is brought to a landing at a floor 14 of the building structure.

To this end, a hand lever 56' is pivoted as at 57' to any portion of the elevator car 15 within convenient range of the attendant. A quadrant 58 is fixedly mounted to the pivotal axis 57 of the lever 56 so as to present a circular series of ratchet teeth 59 in the path of a pawl 60 operated by a thumb lever 61 pivoted to the hand lever 56 as at 62. In consequence thereof, the lever 56 may be maintained in any adjusted position within the limits of the quadrant 58. Rods 63 and 64 are pivoted to each other and the hand

lever 56 about a pin 65 positioned from the axis 57 a sufficient distance to afford the desired displacement of the aligned rods 63 and 64 which, in this instance, are guided by brackets 66 secured to the wall of the elevator car 15 for extension through the floor 32 and ceiling 33 thereof.

Bell cranks 67 are pivoted as at 68 so that the short arms 69 thereof extend for connection to each end 70 of the rods 63 and 64. The longer arms 71 of the bell crank levers 67 are pivoted for connection to a link 72 which has a terminal end thereof operatively connected to levers 73 pivoted as at 74 to the elevator car 15 beyond the floor 32 and ceiling 33 thereof. As shown, the levers 73 have the arms thereof provided with elongated slots 75 and 76 which cooperate with pins 77 and 78, respectively, mounted for slidable movement therein. The pin 77 is carried by a rod 79 mounted for horizontal movement in aligned guide brackets 80 and 81 so that an offset parallel extension 82 thereof will move proximate to one of the trips 34.

To this end, the offset extension 82 is guided in a bracket 83 so as to carry a transversely disposed lug 84 which extends in the path of the trip pin extension 42 (see Figures 1 and 2). Similarly, the pin 78 is carried in a rod 85 guided in brackets 86 so that an offset rod extension 87 will reciprocate in the path proximate to the other trip 34 on the opposite side of the elevator car 15. As shown, the offset extension 87 carries a transverse lug 88 near the extremity thereof to extend in the path of the trip pin extension 42 of the respective trip 34, thereby displacing the pin extensions 41 of the trips 34 to approach each other responsive to the counterclockwise movement of the handle control lever 56. In consequence thereof, the trips 34 will be ineffective to operate doors 16 or the sections 19 and 20 thereof.

The trips 35 have the pin extensions 41 thereof similarly displaced owing to corresponding lever and link instrumentalities, it being noted that the lugs 84 and 88 are normally urged by coil springs 89 to assume their extreme retracted position so as to be inoperative for displacing the trip pins 41. To this end, the coil springs 89 envelop guide rods 90 fastened to brackets 91 so as to normally urge the lever 73 in a clockwise direction (viewed from Figure 1). Moreover, coil springs 92 envelop the rods 63 and 64 for abutment against washers 93 which serve as a fixed support therefor. Pins 94 extend through the rods 63 and 64 so as to serve as a stop for the springs 92 which impart an urge thereto to assist the coil springs 89 in maintaining the lugs 84 and 88 out of engagement with the trip pin extensions 42. For that reason, it is necessary for the attendant to displace the hand control lever 56 against the urge of springs 89 and 92 in order

70

75

80

85

90

110

115

120

125

130

to render the elevator car 15 inoperative to open the doors 16.

Should the attendant desire to bring the elevator car 15 to any desired floor 14 for the purpose of egress or ingress thereto, it will be necessary to displace the hand control lever 56 in a counter-clockwise direction (viewed from Figure 1) prior to the approach thereof. Otherwise, the door 16 will remain closed even though the elevator car 15 arrives at the floor landing 14. Should this occur owing to the untimely displacement of the lever 56, then the elevator car 15 will necessarily have to be moved above or below the latches 26 and 31 so as to effect the opening of the door 16 with the return of the elevator car 15 to the landing 14.

It has been found necessary or at least highly desirable to automatically lock the door 16 or the sections 19 and 20 thereof against displacement from the exterior of the elevator shaft 13. In the present embodiment the door section 19 is provided with a latch 95 which is fixed thereto by fasteners 96 so that the catch 97 thereof will depend therefrom along a vertical median line beyond the meeting edges 21 of the door sections 19 and 20. The other section 20 is provided with a catch 98 complementary to the catch 97, the former being carried by a lever 99 which is pivoted intermediate the extremities thereof about a pin 100.

A coil spring 101 is disposed to bear against the catch 98, it being held in position thereon by means of a pin 102 which extends therefrom for alignment with a correspondingly shaped pin 103 carried by a bracket 104 fixed to the door section 20 as at 105. In consequence thereof, the lever 99 with its catch 98 is urged in a clockwise direction (viewed from Figure 1) to engage its complementary catch 97 which fixedly depends from its bracket 95, thereby preventing a separation of the door sections 19 and 20. Another coil spring 106 is held by a pin 107 fixed to the free extremity of the lever 99 for alignment with a corresponding pin 108 carried by the bracket 109 so as to impart clockwise movement to the lever 99 with increased security and double spring urge.

In order to effect the disengagement between the complementary catches 97 and 98 so as to permit the separation of the door sections 19 and 20 prior to the engagement of the trip pins 41 with the latches 26 or 31 depending upon the directional approach to the doorway 12, rods 110 and 111 are mounted for horizontal reciprocation in guide brackets 112. The rod 110 terminates in the path of the lever 99 on one side of its pivot 100, while the rod 111 terminates in an offset extension 113 which is in the path of the lever 99 on the other side of its pivot 100; therefore, the approach of the rods 110 and 111 will effect a counterclockwise rotation of the

lever 99 to an extent sufficient for effecting disengagement between the catches 97 and 98.

This is accomplished owing to the provision of roller followers 114 fixed to the extremities of the rods 110 and 111 in the path of cams 115, in this instance four. The cams 115 are of arcuate configuration and terminate for disposition in the path of the roller followers 114, they being secured by means of brackets 116 to the elevator car 15 above and below the trip pins 41 thereon so as to release the locking device or complementary catches 97 and 98 just prior to the engagement of the pins 41 with the latches 26 and 31 depending upon the directional approach of the elevator car 15 to the doorway 12. As a consequence, the door sections 19 and 20 will be normally locked against separation responsive to the meeting approach of the door edges 21.

In the event a door 16 comprises a single section, then the catch 98 with its lever 99 is pivoted about a pin 100 fixed to the elevator shaft 13 or any structure held stationary relative thereto. With such an arrangement, the lower latch 31' is fixed to a weight 20' guided for vertical movement along rods 18', thereby conforming in purpose to the lower door section 20. In this connection, the upper section corresponds with an elevator gate 19' (Figure 5) which has latches 26' fixed to the sides thereof in the manner described above in connection with the upper door section 19. A tension transmitting wire or rope 22' is anchored at one extremity thereof to the latch 26' for frictional contact with a peripherally grooved sheave 23' mounted in a corresponding bracket 24' so as to secure the other extremity to the weight 20' as at 28'. A cam 54 is fixed to the wall of the shaft 13' as at 56' in the path of the latch 31', thereby displacing the trip pin 41 when the elevator car recedes beyond the creeping range of the elevator car bottom 32 with respect to the floor landing 14. In consequence thereof, sliding doors of various design and construction may be operated responsive to a movement of the elevator car 15 without resort to intricate operators of known construction, it being noted that the trip pins 41 will also serve to retard the closing movement of the doors 16' even though it constitutes a single section or member.

Various changes may be made in the embodiment of the invention herein specifically described without departing from or sacrificing any of the advantages thereof as defined in the appended claims.

I claim:

1. In an elevator structure, the combination with an elevator shaft, of a movable shaft door, an elevator car in said shaft, and cooperating means on said elevator car and shaft door to effect the opening and closing thereof responsive to the directional move-

ment of said elevator car relative to said shaft door in either direction, said means being effective to control the opening and closing of said door within the acceleration 5 of said elevator car.

2. In an elevator structure, the combination with an elevator shaft, of a horizontally divided movable shaft door composed of a top and bottom section, means for connecting 10 said door sections together for opposed sliding movement to effect the opening and closing of said shaft door, an elevator car in said shaft, and cooperating means rigidly fixed to said elevator car and shaft door in rigid 15 spaced relation to operate said door sections responsive to the approach of said elevator car to said shaft door in either direction.

3. In an elevator structure, the combination with an elevator shaft, of a movable 20 shaft door, an elevator car in said shaft, and cooperating means mounted in rigid spaced relation on said elevator car and shaft door to operate said door responsive to the approaching and receding movement in either 25 direction of said elevator car with respect to said shaft door.

4. In an elevator structure, the combination with an elevator shaft, of a movable shaft door, an elevator car in said shaft, and 30 cooperating means on said elevator car and shaft door to operate said door responsive to the approaching and receding movement in either direction of said elevator car with respect to said shaft door, said cooperating 35 means being effective to control the descent of said door within the receding speed of said elevator car.

5. In an elevator structure, the combination with an elevator shaft, of a movable 40 shaft door, an elevator car in said shaft, cooperating means on said elevator car and shaft door to operate said door responsive to the approaching and receding movement in either direction of said elevator car with 45 respect to said shaft door, and means for rendering said cooperating means ineffective for operating said shaft door.

6. In an elevator structure, the combination with an elevator shaft, of a horizontally 50 divided movable shaft door composed of a top and bottom section, means for connecting said door sections together for opposed sliding movement to effect the opening and closing of said shaft door, an elevator car in said shaft, and cooperating means on said elevator car and shaft door to operate said door sections responsive to the approaching and receding movement in either direction of said elevator car with respect to said shaft door.

7. In an elevator structure, the combination with an elevator shaft, of a horizontally divided movable shaft door composed of a top and bottom section, means for connecting 60 said door sections together for opposed sliding movement to effect the opening and

closing of said shaft door, an elevator car in said shaft, and cooperating means on said elevator car and shaft door to operate said door sections responsive to the approaching and receding movement in either direction of said elevator car with respect to said shaft door, said cooperating means serving to control the closing of said door sections within the receding speed of said elevator car.

8. In an elevator structure, the combination with an elevator shaft, of a horizontally divided movable shaft door composed of a top and bottom section, means for connecting said door sections together for opposed sliding movement to effect the opening and closing of said shaft door, an elevator car in said shaft, and cooperating means on said elevator car and shaft door to operate said door sections responsive to the approaching and receding movement in either direction of said elevator car with respect to said shaft door, said cooperating means serving to control the closing of said door sections within the receding speed of said elevator car, and means for displacing said cooperating means relative to each other for enabling the elevator to pass said shaft door without the operation thereof.

9. In an elevator structure, the combination with an elevator shaft, of a horizontally divided movable shaft door composed of a top and bottom section, means for connecting said door sections together for opposed sliding movement to effect the opening and closing of said shaft door, an elevator car in said shaft, and cooperating means on said elevator car and shaft door to operate said door sections responsive to the approaching and receding movement in either direction of said elevator car with respect to said shaft door, said cooperating means serving to control the closing of said door sections within the receding speed of said elevator car, said cooperating means being positioned for displacement of the bottom door section below the elevator car to permit creeping thereof.

10. In an elevator structure, the combination with an elevator shaft, of a horizontally divided movable shaft door composed of a top and bottom section, means for connecting said door sections together for opposed sliding movement to effect the opening and closing of said shaft door, an elevator car in said shaft, cooperating means on said elevator car and shaft door to operate said door sections responsive to the approaching and receding movement in either direction of said elevator car with respect to said shaft door, means for normally locking said door sections in their closed position, and means on said elevator car for releasing said locking means prior to the engagement of said cooperating means in opening said door sections.

11. In an elevator structure, the combina-

70

tion with an elevator shaft, of a movable shaft door, an elevator car in said shaft, cooperating means on said elevator car and shaft door to operate said door responsive to the approaching and receding movement in either direction of said elevator car with respect to said shaft door, means for normally locking said shaft door against movement from the exterior, and means on said elevator car for releasing said locking means prior to the engagement of said cooperating means in opening said door.

12. In an elevator structure, the combination with an elevator shaft, of a movable shaft door, an elevator car in said shaft, cooperating means on said elevator car and shaft door to operate said door responsive to the approaching and receding movement in either direction of said elevator car with respect to said shaft, means for normally locking said shaft door against movement from the exterior, means on said elevator car for releasing said locking means prior to the engagement of said cooperating means in opening said door, and means for displacing said cooperating means relative to each other for enabling the elevator to pass said shaft door without the operation thereof.

13. In an elevator structure, the combination with an elevator shaft, of a movable shaft door, an elevator car in said shaft, and cooperating means on said elevator car and shaft door to operate said door responsive to the approach of said elevator car to said shaft door in either direction, said cooperating means comprising a lever pivoted to said elevator car, a pivotal lever stop on said shaft door, and a lever camming surface on said elevator shaft in the path of said lever and stop to control the cooperation therebetween.

14. In an elevator structure, the combination with an elevator shaft, of a movable shaft door, an elevator car in said shaft, and cooperating means on said elevator car and shaft door to operate said door responsive to the approach of said elevator car to said shaft door in either direction, said cooperating means comprising a spring impelled lever pivoted to said elevator car, a pivotal lever stop on said shaft door, and a lever camming surface on said elevator shaft in the path of said lever and stop to control the cooperation therebetween.

15. In an elevator structure, the combination with an elevator shaft, of a horizontally divided movable shaft door composed of a top and bottom section, means for connecting said door sections together for opposed sliding movement to effect the opening and closing of said shaft door, an elevator car in said shaft, and cooperating means on said elevator car and shaft door to operate said door sections responsive to the approaching and receding movement in either direction of said elevator car with respect to said shaft

door, said cooperating means serving to control the closing of said door sections within the receding speed of said elevator car, means for displacing said cooperating means relative to each other for enabling the elevator to pass said shaft door without the operation thereof, said cooperating means comprising a lever pivoted to said elevator car, a lever stop on said shaft door, and a lever camming surface on said elevator shaft in the path of said lever and stop to control the cooperation therebetween.

16. In an elevator structure, the combination with an elevator shaft, of a horizontally divided movable shaft door composed of a top and bottom section, means for connecting said door sections together for opposed sliding movement to effect the opening and closing of said shaft door, an elevator car in said shaft, and cooperating means on said elevator car and shaft door to operate said door sections responsive to the approaching and receding movement in either direction of said elevator car with respect to said shaft door, said cooperating means serving to control the closing of said door sections within the receding speed of said elevator car, means for displacing said cooperating means relative to each other for enabling the elevator to pass said shaft door without the operation thereof, said cooperating means comprising a lever pivoted to said elevator car, a lever stop on said shaft door, and a lever camming surface on said elevator shaft in the path of said lever and stop to control the cooperation therebetween, there being cooperating means positioned in the corner regions of said door sections and elevator car.

17. In an elevator structure, the combination with an elevator shaft, of a movable shaft door, an elevator car in said shaft, and cooperating means on said elevator car and shaft door to operate said door responsive to the approach of said elevator car to said shaft door in either direction, said cooperating means comprising a lever pivoted to said elevator car, a lever stop on said shaft door, there being levers pivoted to said elevator car in the corner regions thereof, and stop means in the corner regions of said door to cooperate with said levers, and camming brackets fixed to the said elevator shaft in the path of said levers.

18. In an elevator structure, the combination with an elevator shaft, of a movable shaft door, an elevator car in said shaft, and cooperating means on said elevator car and shaft door to operate said door responsive to the approach of said elevator car to said shaft door in either direction, said cooperating means comprising a lever pivoted to said elevator car, a lever stop on said shaft door, and a lever camming surface on said elevator shaft in the path of said lever and stop to control the cooperation therebetween,

there being levers pivoted to said elevator car in the corner regions thereof, and stop means in the corner regions of said door to cooperate with said levers, and means for normally locking said door against movement, and means in advance of said levers for releasing said locking means.

19. In an elevator structure, the combination with an elevator shaft, of a doorway in 10 said shaft, a movable shaft door mounted in said shaft to close said doorway, an elevator car in said shaft, cooperating means on said elevator car and shaft door to operate said door responsive to the approach of said elevator car to said shaft door in either direction, said cooperating means serving to maintain said door in open position with respect to said doorway while said elevator car is in aligned communication with said doorway 20 or within creeping range thereof.

In witness whereof, I subscribe my name.
LOUIS TORCH.
